UNITED STATES PATENT OFFICE

160,158

DISPLAY DEVICE FOR FINGER RINGS

Hy Frackman, New York, N. Y.

Application July 13, 1949, Serial No. 3,887

Term of patent 3½ years

(Cl. D80—9)

To all whom it may concern:

Be it known that I, Hy Frackman, a citizen of the United States, residing in the Borough of Manhattan, in the city, county, and State of New York, have invented a new, original, and ornamental Design for a Display Device for Finger Rings, of which the following is a specification, reference being had to the accompanying drawing, forming a part hereof, in which:

Fig. 1 is a front elevation of a display device for finger rings, embodying my new design;

Fig. 2 is a top plan view thereof; and

Fig. 3 is a side elevation thereof.

I claim:

The ornamental design for a display device for finger rings, as shown.

HY FRACKMAN.
